UNITED STATES PATENT OFFICE.

ERNEST O. L. VOGT, OF PHILADELPHIA, PENNSYLVANIA.

ADJUSTABLE DELAY DEVICE FOR ORDNANCE-FUSES.

1,032,253.

Specification of Letters-Patent.

Patented July 9, 1912.

Application filed March 16, 1912. Serial No. 684,084.

To all whom it may concern:

Be it known that I, ERNEST OTTO LEOPOLD VOGT, a subject of the Emperor of Germany, having declared my intention of becoming 5 a citizen of the United States, residing in Philadelphia, Pennsylvania, have invented certain Improvements in Adjustable Delay Devices for Ordnance-Fuses, of which the following is a specification.

10 My invention relates to fuses for ordnance; and the object of my invention is to provide means for regulating the detonation of percussion caps or primers carried by a percussion plunger and controlling the explosion of the shell.

15 My invention comprises an adjustable firing pin movable to a plurality of positions, usually two, whereby either of a pair of percussion caps or primers may be exploded; 20 both caps or primers communicating with flame passages leading to the shell bursting charge. Behind one of the primers or percussion caps a delay powder grain is located, by which the ignition of the shell 25 charge can be delayed.

These and other features of my invention are more fully described hereinafter, reference being had to the accompanying drawings forming part hereof, in which:

30 Figure 1, is a sectional elevation of the head of an explosive projectile of the type to which my invention may be applied, showing the firing pin in one position; Fig. 2, is a similar view showing the firing pin in another position; Fig. 3, is a plan view on the line *a—a*, Fig. 1; Fig. 4, is a plan view on the line *b—b*, Fig. 2; Fig. 5, is a view illustrating a detail of the construction shown in Figs. 1 and 2; Fig. 6, is a sectional elevation similar to Figs. 1 and 2, 35 illustrating another form of firing pin and means for adjusting the same; Fig. 7, is an enlarged plan view on the line *c—c*, Fig. 6, and Fig. 8, is a sectional elevation on the line *d—d*, Fig. 6.

40 The delay device includes a percussion plunger 1, and an adjustable firing pin 2. The percussion plunger carries two primers or percussion caps, 3 and 4; the primer or 45 percussion cap 3 being disposed in a passage 5 in the plunger 1, which passage also contains a delay powder grain 6, while the other primer or percussion cap is disposed in a passage 5^a without a delay powder grain. Upon impact and contact of the plunger with the firing pin, delay is ob-

tained when the primer or percussion cap 3 disposed in the passage 5 containing the delay powder grain becomes detonated by engagement with a point 7 carried by said firing pin. Non-delay is obtained when the other primer or percussion cap 4 is detonated.

50 In the drawings, the non-delay position is illustrated in Figs. 1 and 3; the point 7 of the firing pin being disposed toward the left. The firing pin 2 is slideable horizontally; a spring 8 tending, in the position of the structure as illustrated in the drawings, to push the said pin to the right, but the said pin is kept in the illustrated position by the inner wall of a rotary setting plate 9. When a recess 10 formed in the wall of said plate is brought to a position opposite the right end of the pin as illustrated in the drawings, the latter is moved by the spring 8 a limited distance to the right, bringing the point 7 thereof in line with the other primer or percussion cap located in the passage provided with the delay powder grain. 55

55 The form of firing pin shown in Figs. 1, 2, *et seq.*, is hollow, and an internally disposed spring is shown adapted to react upon a plug 11 engaging the wall of the setting plate opposite the end which enters the recess of said setting plate. To insert this firing pin in position, the end of the shell structure is bored at 12 and the firing pin may be round so as to fit the same. As the point 7 projects from the surface of the 60 same it is necessary to provide some means of inserting said pin and this may be accomplished by slotting the bore 12 as indicated at 13; the pin being inserted with the point uppermost and then turned to place such pin in the operative position. It may be held in such position by means of a lug 14 fitting the slot 13. This construction is 65 more fully shown in Fig. 5. It is, of course, possible to organize a structure in which the 70 spring is disposed externally of the pin.

75 In the drawings a setting plate having a single recess is shown. It is of course possible to provide a setting plate having a plurality of recesses, or to replace one of such recesses by a projecting part 10^a on the other side of a setting plate 9^a (diametrically opposite), as shown in Figs. 6, 7 and 8. The setting pin shown in this construction differs slightly from that shown in Figs. 1, 2, *et seq.* 80 It may be made from a round bar, and to form the point 7, the under side is partially

removed as indicated. In such instances, the use of a spring for pushing the pin to the other side is superfluous. In this arrangement the setting plate forms a cam path, the walls of which are equi-distant at all points. In lieu of this arrangement, the setting plate may have a cam groove as illustrated at 15, Fig. 7, in broken lines; the firing pin, in such instance being provided with lugs for operative engagement with such groove.

In the disposal of the setting plates as illustrated in the drawings, they must be moved a quarter turn to effect changes in the position of the firing pin. The operative parts of such setting plates, however, might be set closer to the position of change so as to lessen the amount of movement to effect such changed positions.

20 To insure movement of the percussion plunger with the primers or percussion caps always in position to be engaged by the firing pin whether the latter is in one or the other of its positions, guiding means may be provided. These guiding means may be in the form of a groove 16 formed in the passage, with a corresponding lug 17 carried by such percussion plunger.

I claim:

30 1. The combination with a shell, universal projectile, or the like, of a percussion plunger disposed in said shell, a plurality of percussion caps carried by said plunger, and an adjustable firing pin carried by said shell.

35 2. The combination with a shell, universal projectile, or the like, of a percussion plunger disposed in said shell, a plurality of percussion caps carried by said plunger, an adjustable firing pin carried by said shell, and 40 means for adjusting said pin.

45 3. The combination of a shell, universal projectile, or the like, of a percussion plunger disposed in said shell, a plurality of percussion caps carried by said plunger, a firing pin adjustably mounted within said shell and 50 movable for detonating engagement with either one of said caps, and means including a rotary setting ring for moving said firing pin.

50 4. The combination of a shell, universal

projectile, or the like, of a percussion plunger disposed in said shell, a plurality of percussion caps carried by said plunger, a firing pin adjustably mounted within said shell and movable for detonating engagement 55 with either one of said caps, a rotary ring having a cam path provided with a recess receiving one end of said pin, and a spring for moving said pin when the ring is turned to permit the pin entering said recess. 60

5. The combination with a shell, universal projectile, or the like having a movable percussion plunger disposed in said shell and carrying a plurality of percussion caps, of an adjustable firing pin carried by said shell, and a setting plate having a cam surface for adjusting said pin. 65

6. The combination with a shell, universal projectile, or the like having a movable percussion plunger disposed in said shell and 70 carrying a plurality of percussion caps, of an adjustable firing pin carried by said shell, a setting plate having a cam surface in engagement with said pin, and a spring for moving said pin in one direction upon turning the setting plate. 75

7. The combination with a shell, universal projectile, or the like having a movable percussion plunger with a plurality of percussion caps, of a firing pin adjustably mounted 80 within said shell and movable for detonating engagement with either one of said caps, and a rotatable ring for moving said firing pin having a cam surface contacting with said pin. 85

8. The combination with a shell, universal projectile, or the like having a movable impact or percussion plunger with a plurality of percussion caps, of a firing pin adjustably mounted within said shell and movable for 90 detonating engagement with either one of said caps, and a rotary ring having a cam surface contacting with one end of said pin.

In testimony whereof, I have signed my name to this specification, in the presence of 95 two subscribing witnesses.

ERNEST O. L. VOGT.
